Loans & Pond, Atty's.

UNITED STATES PATENT OFFICE

JOHN V. BURNS, OF KENOSHA, WISCONSIN, ASSIGNOR TO SIMMONS COMPANY, OF NEW YORK, N. Y., A CORPORATION OF DELAWARE

ORTHOPEDIC BED

Application filed April 23, 1930. Serial No. 446,752.

My invention relates to beds, and has to do more particularly with a bed of an orthopedic type suitable for use in hospitals, sanitariums and the like.

5 In the care of patients whose condition is such as to preclude their bodily disturbance, it is desirable that some arrangement be provided whereby the bed-clothing may be changed without requiring movement of the 10 patient.

It is an object of my invention to provide a bed which will meet the above requirement and will have new and improved means for actuating the same.

15 A further object of my invention is to provide such a device having auxiliary means for supporting the body of a patient while the bed-clothing is being changed and with main body-supporting means which may be 20 raised or lowered, with automatic means for limiting the upward movement of the latter and for locking it in position.

Another object is to provide such a device which will be simple in construction, easy 25 to manipulate, certain in operation, efficient, and rugged.

Various other objects and advantages will become apparent to those skilled in the art as the description proceeds.

30 Referring now to the drawing forming a part of this specification and illustrating a preferred embodiment of my invention:

Fig. 1 is a side elevational view of a bed embodying my invention, and

35 Figs. 2, 3 and 4 are sectional views taken respectively on the lines 2-2, 3-3 and 4-4 of Fig. 1.

The numeral 10 indicates generally a bed embodying my invention, the bed having the 40 usual end rails 12 and 12' and side rails 13.

A plurality of clamping members 14 are carried by the side rails for the purpose of securing straps (not shown) formed of canvas or the like, these straps extending across 45 the bed and forming an auxiliary support for the patient.

I also provide a frame 16 to which is secured a fabric spring 18 of any suitable type. To one end of the frame 16 is fastened 50 an angle member 17 (Fig. 2) for a

purpose to be described. The frame 16 is preferably provided with depending legs 19 carrying casters 20.

Secured to the frame 16 by any suitable means such as rivets or the like are straps 22 which are wound around drums 24 eccentrically mounted on shafts 25, 25'. The shafts 25, 25' are rotatably journaled in brackets 26, 26' which may be secured to and depend from the side rails of the bed.

53 Splined on the shafts 25, 25' are worm wheels 28, 28', these worm wheels cooperating with worms 29, 29' mounted on a shaft 30 which extends longitudinally of the bed and is rotatably journaled in the brackets 26, 26'. The shaft 30 is preferably provided 60 with a polygonal head at one end which may be engaged by a removable socket crank 32 or the like for manual rotation.

65 Secured to the shaft 30 adjacent the worm 29 is a radial stud 35 having an enlarged head 36. As shown best in Fig. 2, the head of the stud is preferably beveled to provide a cam surface 37. Slidably mounted in a block 38 secured to the bracket 26 is a pin 70 39 which is arranged substantially parallel to the shaft 30, one end of this pin abutting against a compression helical spring 40 which is retained by means of a screw 41 75 threaded into the block. The other end of the pin 39 is provided with a curved beveled cam face 42. (See Fig. 4.) The pin 39 is also provided with a longitudinal bevel 43, while the side of the pin is also beveled adjacent the end as at 44, so as to provide a 80 substantial area of contact for the stud head 36.

85 Slidably mounted in a cylindrical recess 45 in the block 38 is another pin 46 which bears against a compression helical spring 90 48 seated in the recess. The pin 46 is provided with a triangular notch 50 which is adapted to cooperate wedgingly with the bevel 43 of the pin 39.

95 It will be understood, of course, that the shafts 25, 25' extend across the bed, being journaled in brackets on the other side (not shown) similar to the brackets 26, 26' and carrying drums similar to the drums 24. Hence, it will be apparent that when the 100

shaft 30 is rotated by means of the crank 32, the worms 29, 29', acting through the worm wheels 28, 28', will rotate the shafts 25, 25' carrying the drums and will thus wind or 5 unwind, as the case may be, the straps 22 and raise or lower the bed. It will be understood that when the frame 16 is in lowered position, as shown in Fig. 1, the pins 39 and 46 will be disposed as shown in Figs. 10 3 and 4, the pin 46 being urged downwardly from the block 38 by means of the spring 48, but retained in the block by means of the pin 39 which normally occupies a position as shown in Fig. 4 in wedged relation 15 to the pin 46. When the frame 16 is raised to its maximum elevated position so that the spring 18 is disposed immediately below the straps carried by the brackets 14, the angle member 17 will be moved upwardly into 20 abutment with the pin 46. (See Fig. 2.) Movement of this pin upwardly will disengage it from its wedging engagement with the pin 39, and the latter will be released so that it may be moved outwardly by its 25 spring 40 to the position shown in dotted lines in Fig. 4, the pin being retained from further outward movement by reason of the fact that the shoulder formed at the end of the slot 43 will abut against the pin 46. 30 It will be apparent that the pin 39, projecting outwardly from the block 38, will, by reason of its abutment into the path of the stud 36 on the shaft 30, serve as a lock against further rotation of the shaft 30 and 35 hence against further upward movement of the frame 16. The frame and spring will, of course, be retained in elevated position by reason of the fact that the worms 29, 29' will lock the worm wheels against rotation 40 due to any gravitational pull on the straps 22.

When it is desired to lower the bed, the shaft 30 is rotated in such a direction that the beveled face 37 of the stud 36 is brought 45 into engagement with the cam face 42 of the pin 39, camming the pin back into its slot against the action of the spring 40 where it is retained by reason of its wedging action with the pin 46, the latter being urged into 50 such wedging relation by its spring 48. The reason for making the drums 24 eccentric is so that, when the movable bed frame 16 is in maximum elevated position, a given angle of rotation of the operating crank 32 will 55 result in a relatively slight vertical movement of the frame.

Various changes and modifications within the spirit of my invention will become apparent to those skilled in the art from the 60 description herein given, and hence I do not wish to be limited to the specific embodiment shown or uses mentioned except as set forth in the appended claims, which are to be interpreted as broadly as the state of the art will permit.

I claim as my invention:

1. In combination with a bed frame having a vertically adjustable bottom, means for adjusting the elevation of said bottom, means mounted on said bed frame and rendered operative by engagement with said bottom for stopping the latter at a predetermined elevation, and means carried by said adjusting means and operated by a reverse movement of said adjusting means 70 for rendering said stopping means inoperative.

2. In combination with a bed frame having a vertically adjustable bottom, means for adjusting the elevation of said bottom, 80 means mounted on said bed frame and rendered operative by engagement with said bottom for stopping the latter at a predetermined elevation, and cam means carried by said adjusting means and operated by a 85 reverse movement of said adjusting means for rendering said stopping means inoperative.

3. In combination with a bed frame having a vertically adjustable bed bottom, 90 means for adjusting the elevation of said bottom, a member mounted on said frame and engageable by said bottom when the latter is in position of maximum elevation, a second member controlled by said first 95 member for locking said adjusting means against further raising movement, and means carried by said adjusting means adapted to cooperate with said second member in locking said adjusting means, and, 100 by a reverse movement of said adjusting means, in rendering said second member inoperative to lock said adjusting means.

4. In combination with a bed frame having a vertically adjustable bed bottom, 105 means for adjusting the elevation of said bottom, a member mounted on said frame and engageable by said bottom when the latter is in position of maximum elevation, a second member normally retained by said 110 first member and releasable thereby when said first member is engaged by said bottom for locking said adjusting means against further raising movement, said second member having a cam face, and a third 115 member carried by said adjusting means adapted to cooperate with said second member in locking said adjusting means, and having a cam face adapted to cooperate with the cam face of said second member, 120 by a reverse movement of said adjusting means, for camming said second member out of locking relation with said third member.

5. In combination with a bed frame having a vertically adjustable bed bottom, 125 means for adjusting the elevation of said bottom, a member mounted on said frame and engageable by said bottom when the latter is in position of maximum elevation, 130

resilient means urging said member toward said bed bottom, a second member for locking said adjusting means against further raising movement, resilient means urging 5 said second member toward locking position, said first and second members inter-engaging with each other for restricting the movements thereof by their respective resilient members and wedgingly engaging 10 each other when said second member is not in locking position, said second member having a cam face, and a third member carried by said adjusting means adapted to cooperate with said second member in locking 15 said adjusting means, and having a cam face adapted to cooperate with the cam face of said second member, by a reverse movement of said adjusting means, for camming said second member out of locking relation 20 with said third member and into wedging relation with said first member.

6. In combination with a bed frame having a vertically adjustable bottom, means 25 for adjusting the elevation of said bottom, means mounted on said bed frame for stopping operation of said adjusting means against raising said bottom above a predetermined elevation, and means normally retaining said stopping means in inoperative 30 condition and rendering the same operative upon engagement of said retaining means with said bottom.

7. In combination with a bed frame having a vertically adjustable bottom, means 35 for adjusting the elevation of said bottom, means mounted on said bed frame for stopping operation of said adjusting means against raising said bottom above a predetermined elevation, means normally retaining 40 said stopping means in inoperative condition and rendering the same operative upon engagement of said retaining means with said bottom, and means actuated by said adjusting means, upon a reverse movement thereof, for restoring said stopping means to inoperative condition and said retaining means to its normal retaining 45 position.

JOHN V. BERNS.
